UNITED STATES PATENT OFFICE.

JOHN B. DOWNING, OF ORANGE, NEW JERSEY, ASSIGNOR TO BEAVER MACHINE & TOOL CO. INC., OF NEWARK, NEW JERSEY.

DESIGN FOR A FEED-THROUGH SWITCH.

Application filed August 27, 1925. Serial No. 14,608. Term of patent 7 years.

To all whom it may concern:

Be it known that I, J. B. DOWNING, a citizen of the United States, residing at Orange, in the county of Essex and State of New Jersey, have invented a new, original, and ornamental Design for Feed-Through Switch, of which the following is a specification, reference being had to the accompanying drawing, forming a part thereof.

Figure 1 is a plan view of a feed through switch.

Figure 2 is a side view of same showing my new design.

I claim:

The ornamental design for a feed through switch as shown.

JOHN B. DOWNING.
